UNITED STATES PATENT OFFICE.

EDWARD GEISLER HERBERT, OF MANCHESTER, ENGLAND.

SAWING-MACHINE.

SPECIFICATION forming part of Letters Patent No. 691,139, dated January 14, 1902.

Application filed December 18, 1900. Serial No. 40,234. (No model.)

To all whom it may concern.

Be it known that I, EDWARD GEISLER HERBERT, a subject of the Queen of Great Britain, residing at Manchester, England, have invented 5 certain new and useful Improvements in Sawing-Machines, of which the following is a full and complete specification, such as will enable those skilled in the art to which it appertains to make and use the same.

10 This invention relates to sawing-machines; and the object thereof is to provide an improved machine of this class particularly adapted for use in sawing metal for various purposes, but which may be employed for 15 sawing other substances; and with this and other objects in view the invention consists in a machine for the purpose specified constructed as hereinafter described and claimed.

The invention is fully disclosed in the following specification, of which the accompanying drawings form a part, in which the separate parts of my improvement are designated by the same reference characters in each of the views, and in which—

25 Figure 1 is a side elevation of my improved sawing-machine; Fig. 2, an end elevation thereof; Fig. 3, a plan view; and Figs. 4 and 5, respectively, are views of details of the construction I employ.

30 In the practice of my invention I provide a suitable frame or support, the various parts of which are designated by the reference-letter *a*, and said frame is provided with a bed plate or portion *a*² and near the right-hand 35 end thereof with an upright member *a*³, in which is mounted the main shaft *b*.

The machine is driven by a pulley 2, secured to the main shaft *b* and connected with a wheel or disk *2*^a by means of a starting-lever 40 3, which operates a clutch 4. (Shown in Fig. 3.) The wheel or disk *2*^a transmits, through the connecting-rod 5, eccentrically connected therewith, a reciprocating motion to the saw-frame 6, which slides on guides 7, supported 45 on an arm 8, said arm being mounted on the main shaft *b* or on eccentrics *b*', fixed to or connected with the said main shaft, the said eccentrics being provided in order to impart a rocking motion to the saw, thereby increasing 50 its rate of cutting. Alternatively this rocking motion is obtained by setting the saw 6^a

at an angle with the guides 7, this construction being used either in conjunction with the eccentrics or otherwise. The arm 8 is capable of moving vertically on the shaft *b* or on 55 the eccentrics, it being understood that the saw-frame 6, the saw 6^a, connected therewith, and the other parts connected with the said frame, as hereinafter described, rise and fall with the arm 8, to which they are connected, 60 and this operation results in feeding the saw through the material to be sawed thereby, which material is held by the vise-jaws 9. When the saw has cut through the material, the repetition mechanism comes into action, 65 said repetition mechanism being constructed and operating as follows: A flat spring 10, Figs. 1 and 2, is attached to the saw-frame and engages with a catch 11, mounted longitudinally of the bed or frame of the machine, 70 and during the forward stroke presses said catch forward and downward until it enters a hole 12 in the bed of the machine. The catch 11 is connected by a link or spring 13, Fig. 1, a lever 14, Fig. 3, and a shaft 15, Fig. 75 1, and a lever 16 to a clutch 17, (shown in Fig. 3,) which is in the form of a sprocket-wheel mounted on the main shaft. The sprocket-wheel 17 is thereby caused to revolve, setting in motion a chain 18, mounted thereon and 80 on a cam-wheel 19, mounted on a shaft 19^a in the end of the machine opposite the main shaft *b* and below the bed of the machine, which cam-wheel makes one complete revolution. The cam-wheel 19 is of the form of 85 an ordinary sprocket-wheel and is operated by the chain 18, and said cam-wheel is provided with a cam 19^b and a cam-flange 19^c. The cam-wheel 19 operates a lever 20, which is connected by a link 21 with the arm 8, and 90 the said arm is thereby raised and raises with it the saw-frame 6 until the saw is quite clear of the work or the material on which it operates. The cam-wheel 19 then operates a vise-lever 22, which is provided at its upper end 95 with a nut 23 of one of the vise-jaws 9, and said parts are thereby drawn backwardly, releasing the metal or other material and allowing it to feed forward, as hereinafter described, until it meets with a stop 23^a, mounted 100 on a transverse shaft 39, previously set to regulate the amount of material to be cut off.

The cam-wheel continuously revolves and moves the vise-lever 22, so as to close the vise and grip the material to be sawed, and said cam-wheel moves the lever 20, so as to lower the saw onto the material, and finally the lug 24 on the cam-wheel 19 engages with a lever 25, mounted on the support of the lever 20, which it draws back against the resistance of a spring, and as the cam-wheel continues to revolve the lever 25 is released and the end thereof enters the hole 12 in the bed of the machine from below and forces the catch 11 out of the said hole, thereby releasing the clutch 17, to which the catch 11 is connected, as before described, the clutch 17 being provided with a spring which forces it open when the catch 11 is released from the hole 12. The cam 19 then remains stationary until the next piece of material is cut off, when the same process is repeated.

The manner of feeding the work forward is as follows: The chain 18 passes over a sprocket-wheel 26, mounted above the bed of the frame, and said chain is kept in engagement with said sprocket-wheel by an idler 27, mounted thereover and at one side thereof, and said sprocket-wheel 26 or the shaft thereof is connected by a pair of beveled gears 28, as shown in Fig. 3, with the shaft of a feed-roller 29, on which the material to be sawed rests, and said roller is thereby caused to revolve and to push the material forward against the stop 23^a, as already described.

In Fig. 4 are shown certain parts in detail. The material to be sawed is represented by the reference-letter *w* and rests on the feed-roller 29 and is pressed into close contact therewith by a roller 30, carried on an arm 31, pivoted upon a fixed support 31^a and actuated by a spring 31^b. When the whole of the material has been cut up and no longer keeps the rollers 29 and 30 apart, the top roller 30 and the arm 31 fall, thereby causing the finger 32, connected with the arm 31 or forming part thereof, to engage with a bell-crank lever 33, (shown in Figs. 3 and 4,) which carries a striker 34 (see Fig. 1) in such manner that said striker is brought into engagement with the crank-pin as it revolves, thus causing the bell or gong 35 to ring. The curved portion of the bell-lever 33 passes under the catch 11, and an inclined portion 36 raises the said catch out of the hole 12 in the bed of the machine-frame and releases the clutch 17 and throws the repetition mechanism out of gear.

To recapitulate, when the material is cut up the top roller 30 falls, throwing the repetition mechanism out of gear and ringing the bell or gong 35. The spring 10 is held against the side of the saw-frame 6 by means of a slotted clip 37, as shown in Fig. 4, and said clip acts as a washer also and is held in position by the nut 37^a, which is used to tension the saw-blade 6^a. In case the saw-blade breaks the clip 37 is released and allows the spring 10 to assume the dotted position shown

in Fig. 4, and when the saw-frame falls the spring 10 no longer engages with the catch 11, but passes down beside it, and the saw-frame in this case is able to fall lower than it would if the spring 10 rested on the catch 11, and therefore the saw-frame in this case engages with the curved piece 38, (shown in Figs. 3 and 4,) which is acted on to move the bell-lever 33, thereby moving the bell-lever, as before described, and the effect of this is to set the bell ringing if the saw breaks.

In case only a single cut is required or a single piece to be cut from the material the catch 11 may be pushed to the left-hand side 80 of the inclined piece 36, (shown in Fig. 4,) and in this case the spring 10 does not engage with said catch, but passes down beside it, and the saw-frame descends, as before described, until it engages with the curved piece 85 38 and rings the bell, as before.

Fig. 5 shows the raising-lever 20 and the stop 23. The rod 39, on which the stop is mounted, passes through a hole in the lever 40, which can be readily attached to it by means of a set-screw, and the lever 40 is connected by a link 41 with the raising-lever 20. The effect of this construction is that when the raising-lever 20 is raised by the cam-wheel 19, so as to raise the saw clear of the material, the stop 23 is caused to move to the left until it comes opposite the end of the material as it is fed forward. When the raising-lever 20 falls in lowering the saw onto the material, the stop 23 moves to the right until 100 it is clear of the end of the material, thus preventing any possibility of the detached piece of the material jamming between the stop and the saw-blade and breaking the latter.

The pressure of the saw on the material is regulated by the weight 42, (shown in Figs. 1 and 2,) which is supported by a knife-edge device 44 from a rack 43, which may take the form of a screw for convenience in manufacture. A forked link 45 is freely pivoted about a point on the weight, as shown, and is provided with a knife-edge arm 46, which also rests on the rack, and the effect of this arrangement is that as the inclination of the rack to the horizontal is changed by the raising of the saw the weight moves to the left one tooth of the rack. When the inclination of the rack is again changed by the falling of the saw, the link 45 advances one tooth. Thus the weight advances one tooth after 120 each piece of material is cut off and slowly increases the pressure on the saw, so as to compensate for the blunting of the latter through use. The falling of the saw-frame, however, may be checked by any suitable devices.

Having fully described my invention, I claim as new and desire to secure by Letters Patent—

1. A sawing-machine comprising a frame 130 having a main shaft, and vise-jaws one of which is movable, a vertically-movable saw-

blade carrier mounted on said shaft, devices for feeding the material to be sawed transversely of the frame between the vise-jaws, a sprocket-wheel mounted on the main shaft, a 5 cam sprocket-wheel mounted in the opposite end of the frame, means for gearing said sprocket-wheels in connection, and devices in operative connection with said cam-wheel for raising the saw-carrier, substantially as shown and described.

2. A sawing-machine, comprising a frame, a main shaft mounted therein, and vise-jaws arranged transversely of the frame, a vertically-movable saw-frame connected with the 15 main shaft and adapted to rise and fall, a sprocket-wheel mounted on the main shaft, a corresponding cam sprocket-wheel mounted in the frame of the machine opposite the main shaft, means for gearing said wheels in connection, devices connected with the cam sprocket-wheel for operating one of the vise-jaws, and devices in operative connection with said cam sprocket-wheel for raising the saw-frame, substantially as shown and described.

3. A sawing-machine, comprising a frame, a main shaft mounted therein, a saw-frame connected with said shaft and adapted to rise and fall, vise-jaws connected with the frame, 30 one of which is movable, a sprocket-wheel mounted on the main shaft, a cam sprocket-wheel in the opposite end of the frame, a chain for gearing said sprocket-wheels in connection, devices in operative connection with the cam sprocket-wheel for moving one of the vise-jaws, other devices in operative connection with the cam sprocket-wheel for feeding the material to be sawed transversely of the machine, and devices in connection with said 40 last-named devices for operating an alarm device, substantially as shown and described.

4. A sawing-machine, comprising a frame, a main shaft mounted therein, a saw-frame connected with said shaft and adapted to rise 45 and fall, vise-jaws connected with the frame, one of which is movable, a sprocket-wheel mounted on the main shaft, a cam sprocket-wheel in the opposite end of the frame, a chain for gearing said sprocket-wheels in connection, devices in operative connection with the cam sprocket-wheel for moving one of the vise-jaws, other devices in operative connection with the cam sprocket-wheel for feeding the material to be sawed transversely of the 55 machine and devices in connection with said last-named devices for operating an alarm device, said saw-frame being also provided with a weight-support, and a weight mounted thereon, the connection of the weight with its support being such that said weight moves in the direction of the saw as the saw-frame rises and falls, substantially as shown and described.

5. A sawing-machine, comprising a frame, 65 a main shaft mounted therein, a saw-carrier supported by said shaft and adapted to rise

and fall, devices connected with said shaft for giving the saw-carrier a reciprocating motion, vise-jaws connected with the frame, one of which is movable, and devices for operating 70 the movable vise-jaw, and for giving a vertical movement to the saw-frame, and other devices for feeding the material to be sawed transversely of the frame, substantially as shown and described.

6. A machine of the class described, comprising a frame, a main shaft mounted therein, a saw-support connected with the main shaft and adapted to rise and fall thereon, devices connected with the main shaft for 80 giving the saw-support a reciprocating movement, a sprocket-wheel mounted on the main shaft, another sprocket-wheel in the opposite end of the frame and beneath the bed-plate thereof, vise-jaws connected with the frame, 85 one of which is movable, devices in operative connection with the last-named sprocket-wheel for operating the movable vise-jaws, other devices in connection with said sprocket-wheel for feeding the material to be sawed 90 transversely of the machine, means for giving the saw-carrier a vertical movement, and devices for regulating the pressure of the saw-carrier on the material to be sawed, substantially as shown and described.

7. In a machine of the class described, a frame provided with a main shaft, and vise-jaws, one of which is movable, a vertically-movable saw-carrier mounted on the main shaft and provided with devices for giving it 100 a reciprocating motion, a sprocket-wheel mounted on the main shaft, a cam sprocket-wheel in the opposite end of the frame and beneath the bed-plate thereof, said wheels being geared in connection, devices in connection with the cam sprocket-wheel for moving the movable vise-jaw, other devices in operative connection with said cam sprocket-wheel for giving the saw-carrier a vertical movement, and for feeding the material to be 110 sawed transversely of the machine, and a bell or gong adapted to be operated by the operating devices of the machine at a predetermined time, substantially as shown and described.

8. A sawing-machine, comprising a frame having a main shaft, vise-jaws, one of which is movable, a vertically-movable saw-blade carrier connected with an arm mounted on eccentrics arranged on said main shaft, devices for feeding the material to be sawed 120 transversely of the frame between the vise-jaws, a sprocket-wheel mounted on the main shaft, a cam sprocket-wheel mounted in the opposite end of the frame, said sprocket-wheels being geared in connection, and devices in operative connection with said cam-wheel for raising and lowering the saw-carrier, substantially as shown and described.

9. A sawing-machine, comprising a frame, 130 a main shaft mounted therein, a saw-support connected with the main shaft and adapted

to rise and fall thereon, and devices for regulating the pressure of the saw on the material comprising an automatically - movable weight, the action of which is controlled by the saw as it sinks into the material, substantially as shown and described.

In testimony that I claim the foregoing as

my invention I have signed my name, in presence of the subscribing witnesses, this 23^d day of November, 1900.

EDWARD GEISLER HERBERT.
